Attorney.

UNITED STATES PATENT OFFICE.

JOSEPH GOLDSMITH, OF SEATTLE, WASHINGTON.

ICE-CREAM CABINET.

Application filed May 29, 1924. Serial No. 716,666.

The primary aim and object of the present invention is the provision of a refrigerating device or ice cream cabinet for the storage of ice cream or other refrigerated products, wherein the refrigerant agent or medium of said device or cabinet is completely enclosed and protected from the surrounding air, and the refrigerated contents or products stored within the cabinet are completely and fully protected against contamination by said refrigerant agent or medium and are thereby maintained in a wholesome saleable condition.

With these ends in view the invention resides essentially in the provision of a protective collar adapted to surround and snugly fit the upper end of the refrigerated product container or can of the cabinet, in conjunction with an annular cover adapted to fit within the upper end of the refrigerant container, or tub of said cabinet, and to fit within the upper end of said collar, to thus completely enclose the refrigerant contained in the annular chamber formed between said can and said tub, while effectively and positively preventing the said refrigerant from entering said can and destroying the purity of the contents thereof.

The invention further resides in the provision of an ice cream cabinet requiring the minimum attention to and repacking of the refrigerant medium thereof, whereby the use of such refrigerant medium and the time and energy of the operator is economized and conserved.

The invention further resides in the provision of an ice cream cabinet, that is simple and durable in construction, efficient, reliable and sanitary in use and that may be manufactured at a comparatively low cost.

The invention further resides in the novel construction, combination, adaptation and arrangement of parts, as will hereinafter be more fully described and succinctly defined in the appended claims.

Referring now to the accompanying drawings wherein is illustrated the specific form of the invention, as at present preferred:

Figure 1 is a top plan view of an ice cream cabinet fabricated in accordance with the invention, having certain parts thereof broken away or omitted for clearness of illustration.

Figure 2 is a vertical transverse section taken through 2—2 of Figure 1, and, 55

Figure 3 is an enlarged fragmentary view in medial vertical section of the upper portion of the cabinet.

In the accompanying drawings and in the following description I have elected to illustrate and describe the invention as embodied in a single compartment cabinet, but, manifestly the improvements may be embodied in cabinets having two or more compartments without departing from the spirit of 65 the invention or the benefits derivable therefrom, the present showing being merely by way of illustration.

Referring now to the accompanying drawings wherein like reference characters designate like parts throughout the several views, the numeral 5 designates an outer casing of the ice cream cabinet having a cylindrical inner casing or tub 6 rigidly secured and symmetrically disposed therein, in spaced relation therefrom and having an insulating material or filler 7, such as granulated cork, interposed therebetween, substantially as shown in Fig. 2. The casing or tub 6 is provided contiguous to the lower end with a 80 drain conduit 8 having a stop cock 9 disposed upon the outer end thereof, whereby the accumulated liquid in the tub 6 may be readily drawn off when desired.

Concentrically disposed within the tub 6 85 is a perforated cylindrical ice drum 10 having feet 11 rigidly secured thereto upon the lower end thereof adapted to rest upon the bottom wall of said tub. The external diameter of the ice drum 10 is substantially 90 reduced relative to the internal diameter of the tub 6, to provide an annular space therebetween for crushed ice or other suitable refrigerant 12, while the height of the ice drum 10 is also substantially reduced relative to the height of the tub 6, to thereby dispose the upper end of the said ice drum in a plane below the plane of the upper end of said tub, substantially in the manner and relative planes illustrated in Figures 2 100 and 3.

Concentrically disposed within the ice drum 10 is an ice cream can or container 13 adapted to rest upon the bottom wall of the tub 6 and having an integral external bead 105 14 formed thereon adjacent the upper end

thereof. The external diameter of the can 13 is slightly less than the internal diameter of the perforated ice drum 10, to thereby provide an annular space therebetween, 5 while the height of said can is slightly less than the height of the said drum, as shown in Figures 2 and 3.

Interposed between the upper ends of the ice drum 10 and can 13 and extending upwardly therefrom is a cylindrical protective collar 15 having a gasket 16 seated within an annular groove 17 formed upon the lower end thereof. The gasket 16 is adapted to normally abut and restrainingly engage the 10 external bead 14 formed upon the can 13, to thereby retain the collar 15 in position thereon, and when thus positioned the collar 15 prevents the refrigerant 12 from entering the can 13, thus preserving the condition, as will be readily apparent. 20

Seated within and abutting the upper end of the tub 6 is an annular cover or closure 18 having a downwardly extending and concentrically disposed cylindrical extension or 25 thimble 19 rigidly secured therein, adapted at the lower end thereof to project and fit snugly within the protective collar 15, to thereby completely enclose and protect the 30 refrigerant 12 against the deteriorating action and effect of the surrounding air, while also positively preventing such refrigerant from entering the ice cream can 13.

The ice cream can 13 is provided with a 35 cover 20, of any well known type, having a hand hold 21 rigidly secured thereto. The cover 20 is adapted to normally seat upon the gasket 16, as shown, to thereby positively cut off the contents of the can 13, from 40 the surrounding air, as will be readily understood.

A cover 22 is adapted to seat within and abut the upper end of the annular cover 18, whereby the ice cream cabinet is completely 45 closed and the contents thereof fully protected.

Manifestly with the several elements constituting the ice cream cabinet disposed in the relative positions illustrated in Figure 50 3 clear and unobstructed access is had to the contents of the ice cream can 13 while the refrigerant 12 is fully preserved and protected from the surrounding air and is effectually prevented from entering said can 55 13, thus insuring and assuring of the contents of the can 13 remaining in a wholesome and saleable condition. The double covers 20 and 22 also aid in preserving the contents 60 of the can 13 in the condition above described.

By enclosing the refrigerant medium 12 in the manner shown and described, it will be obvious that the ice cream cabinet herein disclosed embodies the maximum in sanitation, further, the necessity of constantly re-

packing the refrigerant, as obtains in the ice cream cabinets now in use, is reduced to the minimum, thus economizing in the use of such refrigerant and conserving the time and energy of the operator.

In the present disclosure I have illustrated and described the protective collar 15 having a gasket 16 which in conjunction with the annular cover 18 and associated thimble 19 constitute the closure for the refrigerant 12, but, it will be obvious and apparent that such protective collar 15 may be dispensed with, if desired, and the lower end of the thimble 19 provided with the gasket 16, to seat upon the annular bead 14 of the can 13, thus simplifying and reducing the manufacturing cost of the ice cream cabinet herein disclosed.

In practical use and operation the annular space formed by the tub 6 and ice drum 10 is filled with the desired refrigerant 12, a can 13 containing the ice cream or other refrigerated product is then disposed within said ice drum and the protective collar 15 positioned thereon, the annular cover 18 is 90 next positioned to enclose and protect the refrigerant 12 after which the cover 22 is placed upon the annular cover 18. Access is obtained to the can 13 by removing the covers 22 and 20, as is obvious.

While I have herein shown and described my invention with sufficient detail to enable those skilled in the art to understand the mode of construction and the principles involved, it is to be understood that there is 100 no intentional limitation herein to the specific form and precise details of construction of the invention shown and described except as expressly defined by the appended claims, and that various modifications of 105 said construction may be resorted to without departing from the invention, or the benefits derivable therefrom. I also desire to have it understood that certain features of the invention herein shown and described may 110 be employed in other combinations than those herein shown.

Having thus fully shown and described my invention, what I claim as new and desire to secure and protect by United States 115 Letters Patent, is:

1. In a refrigerating device for the storage of refrigerated products, in combination, a refrigerant container, a refrigerated product container disposed within said refrigerant container, a protective collar fitting snugly upon the upper end of said product container and extending upwardly therefrom and an annular cover fitting within the upper end of said refrigerant container 120 having a downwardly directed cylindrical extension secured thereto adapted to project and fit snugly within said collar to completely enclose the contents of said refrigerant container.

2. In a refrigerating device for the storage of refrigerated products, in combination, an insulated refrigerant container, a refrigerated product container disposed within said refrigerant container in spaced relation thereto having the upper end thereof disposed in a plane below the plane of said refrigerant container, a protective collar surrounding and fitting snugly upon the upper end of said product container and extending upwardly therefrom in axial prolongation thereto, an annular cover fitting within the upper end of said refrigerant container having a downwardly extending thimble rigidly secured thereto adapted to project and fit snugly within the upper end of said collar to completely enclose the contents of said refrigerant container, and a closure for said annular cover.
3. In an ice cream cabinet, in combination, a refrigerant holding tub having insulated walls, a perforated drum disposed within said tub in spaced relation to the walls thereof, a can for refrigerated products disposed within said drum in spaced relation to the walls thereof, a collar surrounding and fitting snugly upon the upper end of said can and extending upwardly therefrom, and an annular cover fitting within the upper end of said tub having a downwardly extending thimble secured thereto adapted to project and fit snugly within said collar to completely enclose the refrigerant contents of said tub.
4. In an ice cream cabinet, in combination, a refrigerant holding tub having insulated walls, a perforated drum disposed within said tub in spaced relation to the walls thereof, a can for refrigerated products disposed within said drum in spaced relation to the walls thereof and provided exteriorly adjacent the upper end thereof with an integral annular bead, a collar surrounding the upper end of said can and extending upwardly therefrom having a gas-
- ket disposed within the lower end thereof adapted to seat upon the annular bead of said can and provide a watertight joint therebetween, and an annular cover fitting within the upper end of said tub having a downwardly extending cylindrical thimble rigidly secured thereto adapted to project and fit snugly within the upper end of said collar to completely enclose the refrigerant contents of said tub and protect the said refrigerated products therefrom.
5. In an ice cream cabinet, in combination, an outer casing, a refrigerant holding cylindrical tub rigidly secured within said casing in spaced relation thereto and in insulated relation therefrom, a perforated cylindrical drum concentrically disposed within said tub in spaced relation to the walls thereof, an ice cream can concentrically disposed within said drum in spaced relation to the perforated walls thereof and provided exteriorly contiguous to the upper end thereof with an integral annular bead, a cover for said can, a collar surrounding the upper end of said can and extending upwardly therefrom having an annular groove formed within the lower end thereof, a gasket seating in said groove adapted to abut the annular bead of said can to provide a watertight joint between said can and said collar, an annular cover fitting within and abutting the upper end of said tub having a downwardly extending cylindrical thimble concentrically secured therein adapted to project and fit snugly within the upper end of said collar to completely enclose the refrigerant contents of said tub and to protect the contents of said can therefrom, a closure for said annular cover, and draining means for the refrigerant contents of said tub.

In testimony whereof I affix my signature.

JOSEPH GOLDSMITH.
